UNITED STATES PATENT OFFICE.

CONRAD J. BUSCH, OF WYOMISSING, PENNSYLVANIA.

FOUNTAIN-BRUSH.

1,253,934.

Specification of Letters Patent. Patented Jan. 15, 1918.

Application filed February 27, 1917. Serial No. 151,264.

To all whom it may concern:

Be it known that I, CONRAD J. BUSCH, a citizen of the United States, residing at Wyomissing, in the county of Berks and State of Pennsylvania, have invented certain new and useful Improvements in Fountain-Brushes, of which the following is a specification.

The present invention relates to improvements in fountain brushes of that type embodying means for feeding a substance suitably contained in the body of the brush to the bristle portion thereof.

In carrying out my idea the invention is illustrated herein as adapted for shaving brushes but it will be clear that the scope of the invention is not restricted to such embodiment.

An important phase of these devices lies in their construction by means of which the assembling of the parts is readily accomplished and the renewal or replacement of such parts effected with ease. It is, therefore, comprehended by my invention to provide ejector means for the brush assembled in a unit and including a plunger or piston operable in a feeding tube with which it has interlocking connection enabling the feeding means to be connected with or mounted upon the brush body or displaced therefrom by manipulation of said plunger element.

With the above and other objects in view, this invention consists in the novel construction, combination and arrangement of parts, as hereinafter more particularly pointed out and illustrated in the accompanying drawing, wherein:

Figure 1 is a longitudinal sectional view of a brush constructed in accordance with my invention.

Fig. 2 is a side elevation of the ejector means for said brush.

Figs. 3 and 4 are sectional views on the lines 3-3 and 4-4 respectively of Fig. 1.

Throughout the following detail description, and on the several figures of the drawing, similar parts are referred to by like reference characters.

Referring to the drawing 1 designates the body or handle portion of the brush construction forming the subject-matter of this

invention, said body portion being provided with a chamber 2 to receive the substance which is designed to be fed to the bristle portion 3 of the device. The bristle portion 55 is mounted in a head 4 which has threaded connection with the lower extremity of the handle as indicated at 5 and a threaded aperture 6 extends through the lower portion of the handle so as to receive the ejector 60 means hereinafter more particularly set forth. At the opposite end the handle is provided with a threaded filler cap 7 having a central opening through which the feeding means aforesaid extends. 65

The feeding means above referred to, as clearly shown in Fig. 2 constitutes a unit capable of being attached to the body of the brush for supplying the substance in the chamber 2 to the bristle portion 3, as 70 hereinbefore premised. This unit consists of a feeding tube 8 having an exterior threaded portion 9 adapted to be screwed into the threaded opening 6 in the brush body. The tube 8 extends longitudinally 75 of the handle and through the chamber 2, being formed preferably with a beveled seat 10 for the cap 7. Operable within the tube is a plunger 11, the upper end of which extends through the cap 7 and is provided 80 with a knurled head 12 by which the operator is able to reciprocate the plunger for the purpose of effecting feed of the substance from the chamber 2.

The tube 8 just above the threaded portion is provided with a feed opening or openings preferably the latter, 13, and above these openings the tube 8 is oppositely slotted as at 14, said slots communicating 85 with the feed openings 13 just described. 90 Extending transversely of the plunger and mounted therein so as to project through the feed openings 13 is a guide member or pin 15 and a spring 16 preferably embraces the tube seating upon the said pin at one 95 end and against the opposite extremity of the tube as clearly shown in Fig. 2. The plunger through the instrumentality of the spring is maintained in its innermost position effectively closing the feed tube 8 100 against discharge of its contents. Upon retraction of the plunger 11 outwardly of the

body, the lower extremity thereof is brought into a position above the threaded portion 9 of the tube and uncovers portions of the openings 13 through which the contents of the chamber 2 pass into the tube 8. Upon movement of the plunger inwardly of the tube said contents which have entered the tube are ejected into the bristle portion 3 of the brush. The extent of the withdrawal 10 of the plunger 11 determines the quantity of the material which will be ejected in a single movement of the plunger.

Owing to the extension of the pin 15 into the chamber 2 said pin acts as an agitator 15 for the contents of said chamber so that the latter will not become clogged and will more effectively pass into the feed tube. It is to be understood that in this particular device the chamber is to contain soap either in 20 liquid, powder, or paste form.

The pin 15 by reason of its operation in the feed openings 13 and the slots 14 readily permits reciprocatory movement of the plunger but rotation of the plunger will obviously effect 25 rotation of the tube by virtue of the interlocking connection afforded by this pin in the slotted walls of said tube. Thus the ejecting means may readily be connected to the body of the brush or disconnected therefrom 30 by suitably rotating the head 12 of the plunger. This is an important feature of this device.

When it is desired to fill the chamber 2, the cap 7 is unscrewed and by slightly retracting 35 the plunger 11, the soap may be introduced into the chamber 2, it being understood that the plunger is not withdrawn in this filling operation sufficiently to uncover the feed openings.

40 It will be apparent from the foregoing description that the bristle or brush portion 3 may be renewed as occasion may require by reason of its detachable connection with the handle 1 and the body portion may be 45 sterilized whenever necessary or the ejecting means may be easily removed for replacing of parts or cleansing owing to the facility of the removal of the parts as above described.

Having thus described my invention, what 50 I claim as new is:

1. A brush of the class described comprising a hollow body constituting a supply chamber and means for ejecting the contents of said chamber including a feeding tube having means for connecting the same to the body and into which the said contents are received from the chamber, and a plunger operable in said tube and having operative connection with the latter whereby, on rotation 55 of the plunger, to connect the tube to the body.

2. A brush of the class described comprising a hollow body constituting a supply chamber and means for ejecting the contents

of said chamber including a feeding tube 65 having means for connecting the same to the body and into which the said contents are received from the chamber, a plunger including a manipulating handle operable in said tube, and a pin and slot connection 70 between the plunger and tube for connecting the tube to the body upon rotation of the handle.

3. A brush of the class described comprising a body having a supply chamber and 75 a bristle portion, feeding means for feeding the contents of the chamber to the bristle portion comprising a tube arranged to receive the contents of the supply chamber thereinto and having a threaded portion for 80 connection with the body, a plunger operable in said tube, and means interlocking the plunger with the tube for rotation therewith to effect the connection aforesaid while permitting free reciprocal movement of the 85 plunger.

4. A brush of the class described comprising a body having a soap chamber and a bristle portion, feeding means for feeding the contents of the chamber to the bristle 90 portion comprising a tube extending longitudinally through the chamber aforesaid and having an opening communicating therewith, a plunger in said tube, and projections on the plunger extending through 95 the feed opening aforesaid into the chamber and constituting agitating means for the contents of the chamber, said projections connecting the tube for rotation with the plunger but permitting free reciprocatory 100 movement of the latter.

5. A brush of the class described comprising a body having a soap chamber and a bristle portion, feeding means for feeding the contents of the chamber to the bristle 105 portion comprising a feeding tube extending through the chamber aforesaid, and having a slot therein arranged within the chamber aforesaid, a plunger operable in the tube and extending outwardly of the body portion, 110 and projections extending through the slot in the tube and constituting an interlocking connection between the plunger and tube whereby the latter may be rotated by the plunger.

6. In a shaving brush, the combination 115 with a hollow handle and a bristle portion, of ejecting means comprising a feed tube extending from the handle into the bristle portion and having a threaded portion for 120 connection with the handle, said tube having a lateral feed opening, a plunger operable in said tube, a pin projecting laterally from the plunger and through the feed opening aforesaid, a spring embracing the 125 tube and seated against said pin for effecting movement of the plunger in reciprocation thereof, and a closure cap for the

handle through which the plunger extends and having connection with the feed tube aforesaid.

7. Ejecting means for fountain brushes comprising a feed tube having lateral feed openings at opposite sides, a plunger operable in said tube and normally closing the feed openings aforesaid, a pin mounted in

the plunger and extending laterally through the feed openings aforesaid for establishing interlocking connection between the plunger and the tube, and a spring seated upon said pin for holding the plunger in position normally closing the feed openings. 10

In testimony whereof I affix my signature. 15
CONRAD J. BUSCH.
